(57) **ABSTRACT**

A coil component comprises a coil conductor including a circling portion extending around a coil axis, a base body covering the circling portion, a first external electrode, and a second external electrode. The base body has a first surface intersecting the coil axis, a second surface opposite to the first surface, and an outer surface including a connecting surface connecting the first surface with the second surface. The outer surface of the base body includes a main body portion and at least one high resistance portion. The high resistance portion occupies an area of the connecting surface between the first external electrode and the second external electrode, other than the part occupied by the main body portion. The area extends along an entire length of a circumference of the base body around the coil axis. The high resistance portion has a higher volume resistivity than the main body portion.

COIL COMPONENT, CIRCUIT BOARD, AND ELECTRONIC DEVICE

This application is based on and claims the benefit of priority from Japanese Patent Application Serial No. 2021-58967 (filed on Mar. 31, 2021), the contents of which are hereby incorporated by reference in its entirety.

TECHNICAL FIELD

The present disclosure relates to a coil component, a circuit board, and an electronic device.

BACKGROUND

Various magnetic materials have been used as a material for a base body used in electronic components. Ferrite is often used as the magnetic material for coil components such as inductors. Ferrite is suitable as the magnetic material for an inductor because of its high magnetic permeability.

In recent years, various types of electronic devices such as electronic components have been developed to accept a larger amount of current. For example, an inductor used in a DC/DC converter allows a large current to flow. As a material for a magnetic base body of an inductor used in such a circuit allowing a large current to flow, a soft magnetic material which is resistant to magnetic saturation even with a large current is used. For example, Japanese Patent Application Publication 2007-027354 discloses an inductor having a magnetic base body including metal magnetic particles consisting of soft magnetic material. This type of magnetic base body has an insulating film consisting of insulating material formed on the surface of the metal magnetic particle, where the metal magnetic particles are joined to each other via the insulating film. The insulating film formed on the surface of the metal magnetic particle is made of an insulating material which has a good insulation property such as glass or resin. The metal magnetic particles may be joined to each other by an insulating binding material.

In a known coil component, a coil conductor is embedded in a base body including metal magnetic particles, and a pair of external electrodes are connected to both ends of the coil conductor respectively. The pair of external electrodes needs to be electrically insulated from each other and are therefore disposed apart from each other on the surface of the magnetic base body.

There is a problem that a coil component having a magnetic base body including metal magnetic particles has a low dielectric strength voltage. Specifically, the metal magnetic particles are electrically conductive, and the coil component is therefore subject to a breakdown between the external electrodes disposed on the surface of the magnetic base body and between the coil conductor embedded in the magnetic base body and the external electrodes.

Japanese Patent Application Publication 2020-053608 ("the '608 Publication") discloses a coil component including a base body of a rectangular parallelepiped shape. The base body has external electrodes respectively disposed on a pair of opposed surfaces out of the six surfaces of the base body, which intersect a coil axis of the coil conductor, in order to increase a dielectric strength voltage between the coil conductor and the external electrodes. The coil component disclosed in the '608 Publication can reduce the difference of potential between the coil conductor and the

external electrodes, thereby increasing a dielectric strength voltage between the coil conductor and the external electrodes.

As described above, there is a known coil component that can increase a dielectric strength voltage between the coil conductor and the external electrodes. However, no such technology has been known to increase a dielectric strength voltage between the external electrodes. It is a significant problem to increase a dielectric strength voltage between the external electrodes especially when a distance between the external electrodes is short.

SUMMARY

An object of the present invention is to relieve or reduce at least a part of the above problem. One more specific object of the present invention is to provide a coil component that can increase a dielectric strength voltage between the external electrodes. One more specific object of the present invention is to provide a coil component that can increase a dielectric strength voltage between the external electrodes disposed on a base body including metal magnetic particles.

The other objects of the present invention will be apparent with reference to the entire description in this specification. Instead of or in addition to the above problem, the invention disclosed in this specification may solve a problem acquired from the description in this specification.

The coil component according to one aspect of the present invention comprises: a coil conductor including a circling portion extending around a coil axis; a base body covering at least the circling portion of the coil conductor; a first external electrode disposed on the base body and connecting to one end of the coil conductor; and a second external electrode disposed on the base body and connecting to the other end of the coil conductor. According to one aspect of the present invention, the base body has a first surface intersecting the coil axis and having a long side and a short side, a second surface opposite to the first surface and spaced apart from the first surface and spaced apart from the first surface with a distance shorter than the long side, and an outer surface including a connecting surface connecting the first surface with the second surface. According to one aspect of the present invention, the first external electrode is disposed on the first surface, and the second external electrode is disposed on the second surface. According to one aspect of the present invention, the outer surface of the base body includes a main body portion and at least one high resistance portion, the main body portion including plural metal magnetic particles and occupying a part of the connecting surface, the at least one high resistance portion occupying an area of the connecting surface that is not occupied by the main body portion between the first external electrode and the second external electrode, the at least one high resistance portion having a higher volume resistivity than the main body portion.

According to one aspect of the present invention, the circling portion has an outer circumferential surface opposite the connecting surface of the base body. According to one aspect of the present invention, the at least one high resistance portion extends from the connecting surface to the outer circumferential surface of the circling portion.

According to one aspect of the present invention, the at least one high resistance portion extends to an inner area of the circling portion.

According to one aspect of the present invention, the at least one high resistance portion occupies an entire area of

the connecting surface between the first external electrode and the second external electrode.

According to one aspect of the present invention, the at least one high resistance portion includes a first high resistance portion and a second high resistance portion disposed nearer to the second surface than the first high resistance portion.

According to one aspect of the present invention, the first external electrode includes a first plated layer, and the at least one high resistance portion is disposed to contact the first external electrode.

According to one aspect of the present invention, the second external electrode includes a second plated layer, and the at least one high resistance portion is disposed to contact the second external electrode.

According to one aspect of the present invention, each of the plural metal magnetic particles included in the main body portion includes Fe and at least one element out of Si, Ti and Zr. According to one aspect of the present invention, the at least one high resistance portion includes plural other metal magnetic particles. According to one aspect of the present invention, each of the plural other metal magnetic particles includes Fe and at least one element out of Si, Ti and Zr. According to one aspect of the present invention, a content ratio of a total of Si, Ti and Zr to Fe in each of the plural other metal magnetic particles included in the at least one high resistance portion is higher than a content ratio of a total of Si, Ti and Zr to Fe in each of the plural metal magnetic particles included in the main body portion.

According to one aspect of the present invention, each of the plural other metal magnetic particles includes on a surface thereof an insulating film consisting of insulating material.

According to one aspect of the present invention, the plural other metal magnetic particles have a smaller average particle size than the plural metal magnetic particles included in the main body portion.

According to one aspect of the present invention, a relative magnetic permeability of the at least one high resistance portion is 10% or greater of a relative magnetic permeability of the main body portion.

According to one aspect of the present invention, a relative magnetic permeability of the high resistance portion is less than 10% of a relative magnetic permeability of the main body portion.

The circuit board according to one aspect of the present invention comprises any one of the above-described coil components.

The electronic device according to one aspect of the present invention comprises the above-described circuit board.

According to at least one embodiment of the present invention, it is possible to provide a coil component that can increase a dielectric strength voltage between the external electrodes.

BRIEF DESCRIPTION OF THE DRAWINGS

FIG. 1 is a perspective view schematically showing a coil component according to one embodiment of the present invention.

FIG. 2A is a cross sectional view schematically showing a cross section of the coil component in FIG. 1, cut along a plane extending along a coil axis.

FIG. 2B is a cross sectional view schematically showing a cross section of the coil component in FIG. 1, cut along a plane perpendicular to the coil axis.

FIG. 3A is a cross sectional view schematically showing a cross section of a coil component according to another embodiment of the present invention, cut along a plane extending along the coil axis.

FIG. 3B is a cross sectional view schematically showing a cross section of the coil component in FIG. 3A, cut along a plane perpendicular to the coil axis.

FIG. 4A is a cross sectional view schematically showing a cross section of a coil component according to still another embodiment of the present invention, cut along a plane extending along the coil axis.

FIG. 4B is a cross sectional view schematically showing a cross section of the coil component in FIG. 4A, cut along a plane perpendicular to the coil axis.

FIG. 5 is a cross sectional view schematically showing a cross section of a coil component according to still another embodiment of the present invention, cut along a plane extending along the coil axis.

FIG. 6 is a perspective view schematically showing a coil component according to still another embodiment of the present invention.

FIG. 7 is a cross sectional view schematically showing a cross section of the coil component in FIG. 6, cut along a plane extending along the coil axis.

FIG. 8 is a perspective view schematically showing a coil component according to still another embodiment of the present invention.

FIG. 9 is a cross sectional view schematically showing a cross section of the coil component in FIG. 8, cut along a plane extending along the coil axis.

FIG. 10 is a detailed view of a portion of the cross section shown in FIG. 2B, showing magnetic particles of the base body in accordance with an embodiment.

DESCRIPTION OF THE EMBODIMENTS

Various embodiments of the present invention will be described hereinafter with reference to the appended drawings. Throughout the drawings, the same components are denoted by the same reference numerals. It should be noted that the drawings do not necessarily appear in accurate scales for convenience of description. The following embodiments of the present invention do not limit the scope of the claims. The elements described in the following embodiments are not necessarily essential to solve the problem to be solved by the invention.

A coil component 1 according to one embodiment of the present invention will be described with reference to FIGS. 1 to 3. FIG. 1 is a perspective view schematically showing the coil component 1. FIG. 2A is a cross sectional view schematically showing a cross section of the coil component 1 cut along the I-I line in FIG. 1. FIG. 2B is a cross sectional view schematically showing a cross section of the coil component 1 cut along the II-II line in FIG. 1. As shown, the coil component 1 includes a base body 10, a coil conductor 25 disposed in the base body 10, an external electrode 21 disposed on a surface of the base body 10, and an external electrode 22 disposed on a surface of the base body 10 at a position spaced apart from the external electrode 21. The base body 10 includes a magnetic material. Accordingly, the base body 10 may be referred to as a magnetic base body 10 in this specification. In FIG. 1, the base body 10 appears transparent, such that the coil conductor 25 provided in the base body 10 is shown.

In this specification, the arrangement, dimensions, shapes, and other aspects of the members may be herein described based on the "L axis", the "W axis", and the "T axis" shown

in the drawings. In this specification, the "length" direction, the "width" direction, and the "thickness" direction of the coil component **1** may be herein referred to as the "L axis" direction, the "W axis" direction, and the "T axis" direction, respectively. The "thickness" direction may be also referred to as the "height" direction. The L axis, the W axis, and the T axis are perpendicular to each other.

The coil component **1** may be mounted on a mounting substrate **2a**. The mounting substrate **2a** has land portions **3a**, **3b** disposed thereon. The coil component **1** is mounted on the mounting substrate **2a** by connecting the external electrode **21** to the land portion **3a** and connecting the external electrode **22** to the land portion **3b**. A circuit board **2** according to one embodiment of the present invention includes the coil component **1** and the mounting substrate **2a** having the coil component **1** mounted thereon. The circuit board **2** can be installed in various electronic devices. The electronic devices in which the circuit board **2** can be installed include smartphones, tablets, game consoles, electrical components of automobiles, a server, and various other electronic devices. For clarity, the mounting substrate **2a** and the land portions **3a**, **3b** are not shown in the drawings other than FIG. 1.

The coil component **1** may be an inductor, a transformer, a filter, a reactor and any one of various other coil components. The coil component **1** may be a coupled inductor, a choke coil, and any one of various other magnetically coupled coil components. The coil component **1** may be, for example, a power inductor used in a DC/DC converter. Applications of the coil component **1** are not limited to those explicitly described herein.

The base body **10** is made of magnetic material and formed in a substantially rectangular parallelepiped shape. In one embodiment of the present invention, the base body **10** is configured to have a dimension in the L-axis direction (length dimension) **L1** larger than a dimension in the W-axis direction (width dimension) **W1** and a dimension in the T-axis direction (height dimension) **T1**. For example, the length dimension **L1** is from 1.0 to 6.0 mm, the width dimension **W1** is from 0.5 to 4.5 mm, and the height dimension **T1** is from 0.5 to 4.5 mm. The dimensions of the base body **10** are not limited to those specified herein. The term "rectangular parallelepiped" or "rectangular parallelepiped shape" used herein is not intended to mean solely "rectangular parallelepiped" in a mathematically strict sense. The shape of the base body **10** is not limited to those specified herein.

The base body **10** has a first principal surface **10a**, a second principal surface **10b**, a first end surface **10c**, a second end surface **10d**, a first side surface **10e**, and a second side surface **10f**. The outer surface of the magnetic base body **10** is defined by these six surfaces. The first principal surface **10a** and the second principal surface **10b** are at the opposite ends in the height direction of the base body **10**, the first end surface **10c** and the second end surface **10d** are at the opposite ends in the width direction of the base body **10**, and the first side surface **10e** and the second side surface **10f** are at the opposite ends in the length direction of the base body **10**. The first principal surface **10a** is spaced apart from the second principal surface **10b** with the height dimension **T1**, the first end surface **10c** is spaced apart from the second end surface **10d** with the width dimension **W1**, and the first side surface **10e** is spaced apart from the second side surface **10f** with the length dimension **L1**. As shown in FIG. 1, the first principal surface **10a** lies on the top side of the base body **10**, and therefore, the first principal surface **10a** may be herein referred to as "the top surface." Likewise, the second prin-

cipal surface **10b** may be referred to as "the bottom surface." The coil component **1** is disposed such that the second principal surface **10b** faces the mounting substrate **2a**, and therefore, the second principal surface **10b** may be herein referred to as "the mounting surface." The base body **10** has an outer surface including a surface connecting the first end surface **10c** with the second end surface **10d**, which may be herein referred to as the "connecting surface." In the illustrated embodiment, the first end surface **10c** and the second end surface **10d** are connected by the top surface **10a**, the bottom surface **10b**, the first side surface **10e**, and the second side surface **10f**. The surface including the top surface **10a**, the bottom surface **10b**, the first side surface **10e**, and the second side surface **10f** may be referred to as a "connecting surface" or a "connecting surface of the base body **10**."

As described above, the length dimension **L1** of the base body **10** is larger than the height dimension **T1**. Accordingly, among the sides defining the first end surface **10c**, the sides extending in the L-axis direction (namely, a ridge line between the first end surface **10c** and the top surface **10a** and a ridge line between the first end surface **10c** and the bottom surface **10b**) are long sides of the first end surface **10c**, and the sides extending in the T-axis direction (namely, a ridge line between the first end surface **10c** and the first side surface **10e** and a ridge line between the first end surface **10c** and the second side surface **10f**) are short sides of the first end surface **10c**. In the illustrated embodiment, the base body **10** has a hexahedron shape. The shape of the first end surface **10c** as viewed from the front (as viewed from the W-axis direction) is therefore the same as the cross-sectional shape as the base body **10** shown in FIG. 2B. In the illustrated embodiment, among the four sides defining a cross section of the base body **10** shown in FIG. 2B, the two sides extending in the L-axis direction correspond to the long sides of the first end surface **10c**, and the two sides extending in the T-axis direction correspond to the short sides of the first end surface **10c**. The L-axis direction is a longitudinal direction of the coil component **1**.

In the illustrated embodiment, the surfaces **10a** to **10f** of the base body **10** are shown as flat. Alternatively, the surfaces **10a** to **10f** may be curved. Each of the surfaces **10a** to **10f** is shown to be perpendicular to an adjacent surface. Alternatively, each of the surfaces **10a** to **10f** may not be perpendicular to an adjacent surface. The base body **10** may have rounded corners. The ridge lines of the base body **10**, which indicate borders between adjacent surfaces of the surfaces **10a** to **10f**, may be non-straight lines and may be curved according to the shape and arrangement of the surfaces **10a** to **10f**.

In one embodiment of the present invention, the coil conductor **25** has a circling portion **25A** spirally extending around the coil axis **Ax**. The coil conductor **25** is disposed inside the base body **10**. When the base body **10** is viewed from the W-axis direction, an area inside of the circling portion **25A** of the base body **10** is referred to as a core area **10N**, and an area between the circling portion **25A** and an outer surface of the base body **10** is referred to as a margin area **10S**. In one embodiment, the coil conductor **25** is disposed such that the coil axis **Ax** intersects the first end surface **10c**. The coil axis **Ax** may intersect the second end surface **10d**. The coil conductor **25** may be disposed such that the coil axis **Ax** extends in parallel to at least one of the top surface **10a**, bottom surface **10b**, the first side surface **10e** and the second side surface **10f**. The coil conductor **25** is disposed in the base body **10** such that the coil axis **Ax** intersects the first end surface **10c** of the base body **10**. This allows the circling portion **25A** to have a large dimension in

the longitudinal direction of the coil component 1. As a result, it is possible for the base body 10 having a given dimension to increase inductance of the coil component 1 and suppress magnetic saturation in the core area 10N inside of the circling portion 25A.

In one embodiment of the present invention, the base body 10 may be configured to have a height dimension T1 larger than a width dimension W1. This allows the circling portion 25A to have a large dimension in the T-axis direction. As a result, it is possible for the base body 10 having a given dimension to further increase inductance of the coil component 1 and suppress magnetic saturation in the core area 10N inside of the circling portion 25A.

In one embodiment of the present invention, the base body 10 has a main body portion 11 and a high resistance portion 12. The high resistance portion 12 is a portion having a higher volume resistivity than the main body portion 11 among the base body 10. In the drawings, a border between the main body portion 11 and the high resistance portion 12 is shown. However, in a base body of an actual coil component that the present invention is applied, a border may not be visible between a portion corresponding to the main body portion 11 and a portion corresponding to the high resistance portion 12. The volume resistivity of the high resistance portion 12 is for example $1 \times 10^6 \Omega \cdot \text{cm}$ or greater, preferably $1 \times 10^8 \Omega \cdot \text{cm}$ or greater. The base body 10 may include one or more high resistance portions 12. The base body 10 in the coil component 1 includes a single high resistance portion 12. The main body portion 11 may be defined as an area of the base body 10 other than the high resistance portion 12. The base body 10 may include an element other than the main body portion 11 and the high resistance portion 12. The main body portion 11 occupies a part of the connecting surface of the base body 10. In the embodiment shown in FIGS. 2A and 2B, the high resistance portion 12 occupies a part of the connecting surface of the base body 10 near a center of the base body 10 in the W-axis direction, and the main body portion 11 occupies the remaining part of the connecting surface. The high resistance portion 12 is composed of a material for exhibiting a higher volume resistivity than the main body portion 11. A higher percentage of the high resistance portion 12 occupying the base body 10 can cause a magnetic property of the coil component 1 to deteriorate. For example, if the high resistance portion 12 covers all the connecting surface of the base body 10, this can cause a magnetic property of the coil component 1 to deteriorate. Accordingly, at least a part of the connecting surface of the base body 10 is occupied by the main body portion 11.

A relative magnetic permeability of the high resistance portion 12 may be 10% or less of a relative magnetic permeability of the main body portion 11. Accordingly, the high resistance portion 12 can function as a magnetic gap to suppress the occurrence of magnetic saturation in the coil component 1. A relative magnetic permeability of the high resistance portion 12 may be 10% or greater of a relative magnetic permeability of the main body portion 11. Accordingly, it is possible to prevent reduction of inductance due to the high resistance portion. The relative magnetic permeability of the high resistance portion 12 can be determined in accordance with the characteristic required for the coil component 1.

In the illustrated embodiment, the high resistance portion 12 is disposed between the external electrode 21 and the external electrode 22 in the W-axis direction. More specifically, in the illustrated embodiment, the high resistance portion 12 is disposed at the same position as the via

conductor V6 in the W-axis direction. The high resistance portion 12 forms a part of the outer surface of the base body 10. That is, the high resistance portion 12 is exposed on the outer surface of the base body 10. The high resistance portion 12 extends along an entire length of a circumference of the base body 10 around the coil axis Ax. The high resistance portion 12 occupies a part of an area between the external electrode 21 and the external electrode 22 on the connecting surface of the base body 10 in the W-axis direction. In the embodiment shown in FIG. 2, the high resistance portion 12 occupies an area other than the area indicated by the main body portion 11 among the connecting surface of the base body 10. With the above-described structure and arrangement of the high resistance portion 12, going from the external electrode 21 to the external electrode 22 through the outer surface (connecting surface) of the base body 10 along the W-axis direction always includes crossing the high resistance portion 12. In other words, the high resistance portion 12 intervenes between the external electrode 21 and the external electrode 22 on the connecting surface of the base body 10. The high resistance portion 12 may extend into the base body 10. In other words, the high resistance portion 12 may extend to any position between the outer surface of the base body 10 and the coil axis Ax in a radial direction having the coil axis AX as a center and perpendicular to the coil axis Ax.

In one embodiment of the present invention, the base body 10 is composed of magnetic material. As a magnetic material for the base body 10, for example, a soft magnetic alloy material can be used. The soft magnetic metal material for the base body 10 may be, for example, (1) metal Fe or metal Ni, (2) an Fe—Si—Cr alloy, an Fe—Si—Al alloy, or an Fe—Ni alloy, (3) an amorphous Fe—Si—Cr—B—C, or Fe—Si—B—Cr, or (4) a mixed material obtained by mixing these materials. The soft magnetic metal material for the base body 10 may include at least one of Si and Zr, instead of or in addition to Si. The base body 10 may be composed of plural metal magnetic particles 14, 16 consisting of soft magnetic metal material. The surfaces of the plural metal magnetic particles 14, 16 included in the base body 10 are formed thereon with insulating films 18, 20 (respectively). Each of the plural metal magnetic particles 14, 16 included in the base body 10 may be joined to an adjacent metal magnetic particle via an insulating film. The insulating film may include oxide of a constituent element of the metal magnetic particle or may be made of an insulating material other than the constituent element of the metal magnetic particle. In one embodiment, a relative magnetic permeability of the magnetic material for the base body 10 is less than 100. The base body 10 may include a resin. The base body 10 may include a resin binding material that binds the metal magnetic particles consisting of soft magnetic metal material. The binding material consists of, for example, thermosetting material having a good insulation property. The resin material used for a binding material has a smaller magnetic permeability than the first magnetic material. The resin material used for a binding material may be an epoxy resin, a polyimide resin, a polystyrene (PS) resin, a high-density polyethylene (HDPE) resin, a polyoxymethylene (POM) resin, a polycarbonate (PC) resin, a polyvinylidene fluoride (PVDF) resin, a phenolic resin, a polytetrafluoroethylene (PTFE) resin, or a polybenzoxazole (PBO) resin.

The high resistance portion 12 may include metal magnetic particles of a different type from those included in the main body portion 11. For example, the metal magnetic particles 16 included in the high resistance portion 12 have a smaller average particle size than the metal magnetic

particles **14** included in the main body portion **11**. The “average particle size” of the metal magnetic particles in this specification are determined in the following manner. The base body **10** is cut along the thickness direction (the T axis direction) to expose a sectional surface. The sectional surface is photographed using a scanning electron microscope (SEM) to obtain an SEM image at 1000 to 2000-fold magnification, and the particle size distribution is determined based on the SEM image. The particle size distribution obtained in this way is used to determine the average particle size. For example, the 50th percentile (D50) of the particle size distribution obtained based on the SEM image can be used as the average particle size of the metal magnetic particles. Each of the metal magnetic particles has an insulating film on its surface. This allows a volume resistivity of the high resistance portion **12** including metal magnetic particles **16** having a relatively small average particle size to be larger than a volume resistivity of the main body portion **11** including metal magnetic particles **14** having a relatively large average particle size. For example, the metal magnetic particles **14** included in the main body portion **11** have an average particle size from 2 to 20 μm , and the metal magnetic particles **16** included in the high resistance portion **12** have an average particle size from 0.5 to 3 μm .

In one embodiment of the present invention, the dimension of the high resistance portion **12** in the W-axis direction is triple or more the average particle size of the plural metal magnetic particles included in the high resistance portion **12**. If the average particle size of the plural metal magnetic particles included in the high resistance portion **12** is 0.5 μm as described above, the dimension of the high resistance portion **12** in the W-axis direction is 1.5 μm or greater.

For example, a composition of the metal magnetic particle included in the high resistance portion **12** may be different from or the same as a composition of the metal magnetic particle included in the main body portion **11**. A volume resistivity of the metal magnetic particles including Fe gets higher according to a content ratio of Si, Ti or Zr to Fe. In one embodiment of the present invention, a content ratio of a total of Si, Ti and Zr to Fe in each of the plural metal magnetic particles included in the high resistance portion **12** is higher than a content ratio of a total of Si, Ti and Zr to Fe in each of the plural metal magnetic particles included in the main body portion **11**. For example, a content ratio of a total of Si, Ti and Zr to Fe in each of the plural metal magnetic particles included in the high resistance portion **12** is, for example, 10% or greater. A content ratio of a total of Si, Ti and Zr to Fe in each of the plural metal magnetic particles included in the main body portion **11** is, for example, less than 10%. The content ratio of elements in the metal magnetic particle in this specification indicates a content ratio of elements in the metal magnetic particle included in the base body **10** after having subjected to a heat treatment.

As described above, the coil conductor **25** has one end exposed out of the first end surface **10c** and is connected to the external electrode **21** at the one end exposed out of the first end surface **10c**. The coil conductor **25** has the other end exposed out of the second end surface **10d** and is connected to the external electrode **22** at the other end exposed out of the second end surface **10d**. Accordingly, the circling portion **25A** of the coil conductor **25** is embedded in the base body **10**. In other words, the circling portion **25A** is covered by the outer surface of the base body **10**. In the illustrated embodiment, the coil conductor **25** has opposite ends exposed out of the base body **10**, and all the other portions of the coil conductor **25** are disposed inside the base body **10**. In one

embodiment of the present invention, one end of the coil conductor **25** is exposed out of the first end surface **10c** of the base body **10** at a position nearer to the top surface **10a** than the bottom surface **10b**. The other end of the coil conductor **25** is exposed out of the second end surface **10d** of the base body **10** at a position nearer to the top surface **10a** than the bottom surface **10b**.

In the illustrated embodiment, the coil conductor **25** includes conductor patterns **C1** to **C8** extending around the coil axis **Ax** and via conductors **V1** to **V11** extending along the coil axis **Ax**. Each of the conductor patterns **C1** to **C8** is extended by about a $\frac{1}{2}$ turn (about 180 degrees) in a circumferential direction of the coil axis **Ax**. Each of the conductor patterns **C1** to **C8** is connected to an adjacent conductor pattern by a corresponding via conductor among the via conductors **V3** to **V9**. For example, the conductor pattern **C1** is connected to an adjacent conductor pattern **C2** by the via conductor **V3**. The via conductors **V2** to **V10** are connected to the ends of the conductor patterns **C1** to **C8** at one end of the circumferential direction. For example, one end of the conductor pattern **C1** is connected to the via conductor **V1** and the other end is connected to the via conductor **V2**. The conductor patterns **C1** to **C8** and the via conductors **V3** to **V9** are connected in this manner to form a circling portion **25A** spirally extending around the coil axis **Ax**. One end of the circling portion **25A** is connected to the external electrode **21** via the via conductors **V2**, **V1**, and the other end of the circling portion **25A** is connected to the external electrode **22** via the via conductors **V10**, **V11**. The via conductors **V1** and **V2** are leading conductors for connecting the one end of the circling portion **25A** to the external electrode **21**. The via conductors **V10** and **V11** are leading conductors for connecting the other end of the circling portion **25A** to the external electrode **22**. The illustrated shape and arrangement of the conductor patterns **C1** to **C8** are only examples. Various shapes of the conductor pattern other than the shown examples of the present invention can be applied.

In one embodiment of the present invention, the external electrode **21** is disposed on the first end surface **10c** of the base body **10**, and the external electrode **22** is disposed on the second end surface **10d** of the base body **10**. In the illustrated embodiment, the external electrode **21** and the external electrode **22** have a five-sided electrode shape where the external electrode **21** and the external electrode **22** contact five of the six outer surfaces of the base body **10**. Specifically, the external electrode **21** includes a main electrode portion **21a** covering the first end surface **10c** of the base body **10**, a plate-like flange portion **21b** connecting to a negative side end of the main electrode portion **21a** in the L-axis direction and extending along the first side surface **10e** of the base body **10**, a plate-like flange portion **21c** connecting to a positive side end of the main electrode portion **21a** in the L-axis direction and extending along the second side surface **10f** of the base body **10**, a flange portion **21d** connecting to a bottom end of the main electrode portion **21a** and extending along the bottom surface **10b** of the base body **10**, and a flange portion **21e** connecting to a top end of the main electrode portion **21a** and extending along the top surface **10a** of the base body **10**. The external electrode **22** includes a main electrode portion **22a** covering the second end surface **10d** of the base body **10**, a plate-like flange portion **22b** connecting to a negative side end of the main electrode portion **22a** in the L-axis direction and extending along the first side surface **10e** of the base body **10**, a plate-like flange portion **22c** connecting to a positive side end of the main electrode portion **22a** in the L-axis direction

11

and extending along the second side surface **10f** of the base body **10**, a flange portion **22d** connecting to a bottom end of the main electrode portion **22a** and extending along the bottom surface **10b** of the base body **10**, and a flange portion **22e** connecting to a top end of the main electrode portion **22a** and extending along the top surface **10a** of the base body **10**. The illustrated configuration and arrangement of the external electrode **21** and the external electrode **22** are only examples. The configuration and arrangement of the external electrode **21** and the external electrode **22** can be changed accordingly unless there is inconsistency with the effects of the invention as claimed.

The external electrode **21** and the external electrode **22** are arranged such that the tip ends of corresponding flange portions are opposite to each other. For example, as explicitly shown in FIG. 2A, a tip end of the flange portion **21d** (a positive side end in the W-axis direction) of the external electrode **21** is opposite to a tip end (a negative side end in the W-axis direction) of the flange portion **22d** of the external electrode **22**. The external electrode **21** and the external electrode **22** are configured and arranged to be spaced apart from each other with a distance **W2**. Specifically, as shown in FIG. 2A, the distance between the tip ends of the corresponding flange portions is referred to as “**W2**.”

The external electrode **21** is connected to the land portion **3a** at any one of the flange portions **21b** to **21e**. The external electrode **22** is connected to the land portion **3b** at any one of the flange portions **22b** to **22e**. In the illustrated embodiment, the external electrode **21** is connected to the land portion **3a** at the flange portion **21d**, and the external electrode **22** is connected to the land portion **3b** at the flange portion **22d**.

The external electrode **21** may include plural layers including a base electrode layer and a plated layer. The base electrode layer may be formed by applying a conductive paste on a surface of the base body **10** and heating the conductive paste. The conductive paste is a paste obtained by mixing and kneading metal particles such as Ag with a resin. The plated layer is, for example, a nickel-plated layer. The plated layer is formed on a surface of the base electrode layer by, for example, an electrolytic plating method. The plated layer may be double-layer. In a case where the plated layer is double-layer, the first plated layer contacting the base electrode layer may be a nickel-plated layer and the second plated layer formed on the first plated layer may be a tin-plated layer. As with the external electrode **21**, the external electrode **22** may include plural layers including a base electrode layer and a plated layer. Unless there is inconsistency, the description relating to the external electrode **21** applies to the external electrode **22**.

In the illustrated embodiment, the first end surface **10c** and the second end surface **10d** are covered by the external electrode **21** and the external electrode **22** respectively. This prevents magnetic flux flowing in the base body **10** along the coil axis **Ax** from leaking out of the base body **10** through the first end surface **10c** or the second end surface **10d** when a current flows in the coil conductor **25**. Accordingly, it is possible to increase inductance of the coil component **1**. In the illustrated embodiment, one end of the coil conductor **25** is exposed out of the first end surface **10c** of the base body **10** at a position nearer to the top surface **10a** than the bottom surface **10b**, and the other end of the coil conductor **25** is exposed out of the second end surface **10d** of the base body **10** at a position nearer to the top surface **10a** than the bottom surface **10b**. This allows magnetic flux flowing in the circling portion **25A** along the coil axis **Ax** to, after flowing out of the circling portion **25A**, flow in an area between the

12

coil conductor **25** and the top surface **10a** more than an area between the coil conductor **25** and the bottom surface **10b**. Accordingly, it is possible to further reduce leakage of the magnetic flux from the bottom surface **10b**.

5 The coil component **1** has the high resistance portion **12** between the external electrode **21** and the external electrode **22** on the connecting surface on an outer surface of the base body **10**. This prevents a leak current from flowing along the connecting surface of the base body **10** between the external electrode **21** and the external electrode **22**. As shown in FIG. 10 15 2A, the external electrode **21** and the external electrode **22** are closest at the tip ends of the flange portions (for example, the flange portion **21d** and the flange portion **22d**) disposed 20 opposite to each other. This causes a leak current to flow between the external electrode **21** and the external electrode **22** along the connecting surface of the base body **10** when a breakdown occurs between the external electrode **21** and the external electrode **22**. The coil component **1** has the high 25 resistance portion **12** between the external electrode **21** and the external electrode **22** on the connecting surface on an outer surface of the base body **10**. This prevents a leak current from occurring between the external electrode **21** and the external electrode **22**. Accordingly, it is possible to increase a dielectric strength voltage between the external electrode **21** and the external electrode **22**.

An example method for manufacturing a coil component **1** according to one embodiment of the present invention will now be described. The coil component **1** may be manufactured by the sheet laminating method. Specific steps for 30 manufacturing the coil component **1** by the sheet laminating method will be described.

For manufacturing the coil component **1** by the sheet laminating method, first, a magnetic sheet in the form of a sheet is fabricated from a magnetic material. Plural magnetic sheets are then fabricated. The magnetic sheet is formed such that the sheet has a rectangular shape having a long side with substantially the length dimension **L1** and a short side with substantially the height dimension **T1**. The magnetic sheet is fabricated by, for example, mixing and kneading 35 metal magnetic particles with a resin to obtain slurry and placing the slurry in a mold where a predetermined molding pressure is applied. The resin to be mixed and kneaded with metal magnetic particles may be, for example, a resin having a good insulation property such as polyvinyl butyral (PVB) resin or epoxy resin.

45 Next, through-holes for disposing the via conductors **V1** to **V11** are formed in the magnetic sheets. The magnetic sheet formed with a through-hole for disposing the via conductor **V6** is also formed with a ring-shaped through-hole for disposing the high resistance portion **12**. Following this, a conductive paste is applied on the magnetic sheets formed with through-holes by a known method such as 50 screen printing, so that unfired conductor patterns are formed, which will be conductor patterns **C1** to **C8** after firing. At this time, the through-holes formed in the magnetic sheets are filled in with the conductive paste to form unfired via conductors, which will be via conductors **V1** to **V11** after 55 firing. The ring-shaped through-hole formed in the magnetic sheet which is filled with an unfired via conductor to be the via conductor **V6** is filled with slurry, which is obtained by mixing and kneading metal magnetic materials with a resin, by, for example, screen printing. As a result, a precursor of the high resistance portion **12** is formed in the ring-shaped through-hole. The metal magnetic particles included in the slurry filling the ring-shaped through-hole may have a smaller average particle size than the metal magnetic particles included in the material for the magnetic sheet.

The magnetic sheets formed with plural unfired conductor patterns, plural unfired via conductors, and/or precursors of high resistance portions 12 are stacked together. The stacked magnetic sheets are bonded together by thermal compression to fabricate a sheet laminate. Next, the sheet laminate is diced to a desired size by using a cutter such as a dicing machine or a laser processing machine to make a chip laminate.

The chip laminate is then defatted. The defatted chip laminate is subjected to a heat treatment. The heat treatment for the chip laminate is performed at a temperature of, for example, from 400 to 900 degrees Celsius for from 20 to 120 minutes. Accordingly, the base body 10 including the coil conductor 25 inside is produced. With the heat treatment, the high resistance portion 12 is obtained from its precursor.

Next, the external electrode 21 and the external electrode 22 are formed on a surface of the base body 10 obtained by the heat treatment. The external electrode 21 is formed by applying a conductive paste on the first end surface 10c of the base body 10 to form a base electrode layer and then forming a plated layer on a surface of the base electrode layer by, for example, an electrolytic plating method. The plated layer may be double-layer. In a case where the plated layer is double-layer, the first plated layer contacting the base electrode layer may be a nickel-plated layer and the second plated layer formed on the first plated layer may be a tin-plated layer.

By the above-described process, the coil component 1 can be obtained. In the manufacturing method of the coil component 1 as described above, a direction of stacking the magnetic sheets corresponds to the W-axis direction in FIG. 1 to FIG. 3. Specifically, each of the plural magnetic sheets is a plate-like sheet extending along the T-L surface, and these plural magnetic sheets are stacked together in the W-axis direction.

The coil component 1 may be manufactured by a known method other than the sheet fabrication method, such as a compression molding method, a slurry build method, or a thin film processing method.

Next, a coil component 101 according to another embodiment of the present invention will be described with reference to FIGS. 3A and 3B. FIGS. 3A and 3B show cross sectional views of the coil component 101 respectively. FIG. 3A shows a cross section of the coil component 101 cut along a plane along which the coil axis Ax extends. FIG. 3B shows a cross section of the coil component 101 cut along a plane to which the coil axis Ax is perpendicular. The coil component 101 differs from the coil component 1 in that it includes a high resistance portion 112 instead of the high resistance portion 12.

As shown in FIG. 3A and FIG. 3B, the circling portion 25A has a circumferential surface opposite to the connecting surface of the base body 10 (i.e., the top surface 10a, the bottom surface 10b, the first side surface 10e, and the second side surface 10f). The high resistance portion 112 extends from the connecting surface of the base body 10 to the circumferential surface of the circling portion 25A in a radial direction having the coil axis Ax as a center. The high resistance portion 112 prevents a leak current from flowing between the external electrode 21 and the external electrode 22 through inside of the connecting surface of the base body 10, which is an inner side of the base body 10 in the radial direction having the coil axis Ax as a center. Accordingly, the coil component 101 can further increase a dielectric strength voltage between the external electrode 21 and the external electrode 22,

Next, a coil component 201 according to still another embodiment of the present invention will be described with reference to FIGS. 4A and 4B. FIGS. 4A and 4B show cross sectional views of the coil component 201 respectively. FIG. 4A shows a cross section of the coil component 201 cut along a plane along which the coil axis Ax extends. FIG. 4B shows a cross section of the coil component 201 cut along a plane to which the coil axis Ax is perpendicular. The coil component 201 differs from the coil component 1 in that it includes a high resistance portion 212 instead of the high resistance portion 12.

As shown in FIG. 4A and FIG. 4B, the high resistance portion 212 extends from the connecting surface of the base body 10 to the coil axis Ax in a radial direction having the coil axis Ax as a center. Therefore, the high resistance portion 212 occupies a part of a core area 10N of the base body 10.

The high resistance portion 212 prevents a leak current from flowing between the external electrode 21 and the external electrode 22 through the core area 10N of the base body 10. For example, it is possible to prevent a leak current from flowing between the main electrode portion 21a of the external electrode 21 and the main electrode portion 22a of the external electrode 22. A precursor of the high resistance portion 212 can be easily fabricated by mixing and kneading metal magnetic particles with a resin to obtain slurry, compressing the slurry to form a sheet, and forming on the sheet a through-hole for disposing a via conductor V6. Specifically, when the coil component 201 is manufactured by the sheet lamination method, it is not necessary to form a through-hole to be filled with a precursor of the high resistance portion 212 of the magnetic sheet. Accordingly, the coil component 201 can be manufactured by a simpler process than the coil component 1

In the illustrated embodiment, a single high resistance portion 212 is disposed between the conductor pattern C4 and the conductor pattern C5. Alternatively, the coil component 201 may include plural high resistance portions 212. For example, the coil component 201 may include another high resistance portion 212 between the conductor pattern C2 and the conductor pattern C3.

Next, a coil component 301 according to still another embodiment of the present invention will be described with reference to FIG. 5. FIG. 5 shows a cross sectional view of the coil component 301. FIG. 5 shows a cross section of the coil component 301 cut along a plane extending along the coil axis Ax. The coil component 301 differs from the coil component 1 in that it includes a high resistance portion 312 instead of the high resistance portion 12.

In the embodiment shown in FIG. 5, the high resistance portion 312 occupies an entire area between the external electrode 21 and the external electrode 22 on the connecting surface of the base body 10. Specifically, the high resistance portion 312 extends from the positive side ends of the flange portions 21b to 21e in the W-axis direction to the negative side ends of corresponding ones of the flange portions 22a to 22e in the W-axis direction. Accordingly, an entire area of the connecting surface of the base body 10 is occupied by the high resistance portion 312. In the coil component 301, the outer surface of the main body portion 11 of the base body 10 is covered by the external electrode 21, the external electrode 22, and the high resistance portion 312.

The coil component 301 has the high resistance portion 312 occupying an entire area of the connecting surface of the base body 10 between the external electrode 21 and the external electrode 22. This can make sure to prevent a leak current from flowing along the connecting surface of the

15

base body 10 between the external electrode 21 and the external electrode 22. Accordingly, the coil component 301 can further increase a dielectric strength voltage between the external electrode 21 and the external electrode 22.

Next, a coil component 401 according to still another embodiment of the present invention will be described with reference to FIGS. 6 and 7. FIG. 6 is a perspective view schematically showing the coil component 401. FIG. 7 shows a cross section of the coil component 401 in FIG. 6, cut along the line I-I. The coil component 401 differs from the coil component 201 in that it includes an external electrode 121 instead of the external electrode 21 and an external electrode 122 instead of the external electrode 22.

As shown in FIG. 6 and FIG. 7, the external electrode 121 covers only the first end surface 10c of the base body 10, and the external electrode 122 covers only the second end surface 10d of the base body 10. In the illustrated embodiment, the external electrode 121 covers the entire surface of the first end surface 10c of the base body 10, and the external electrode 122 covers the entire surface of the second end surface 10d of the base body 10. The external electrode 121 may cover only a part of the first end surface 10c of the base body 10, and the external electrode 122 may cover only a part of the second end surface 10d of the base body 10. The external electrode 121 is extended to a bottom end of the first end surface 10c, and the external electrode 121 is connected to the land portion 3a at the bottom end. As with the external electrode 121, the external electrode 122 is extended to a bottom end of the second end surface 10d, and the external electrode 122 is connected to the land portion 3b at the bottom end.

As is the case with the coil component 401 where the external electrode 121 covers only the first end surface 10c of the base body 10 and the external electrode 122 covers only the second end surface 10d of the base body 10, a leak current is likely to flow between the external electrode 121 and the external electrode 122 not only on the connecting surface but also inside of the base body 10. According to the coil component 401, the high resistance portion 212 extending from the connecting surface of the base body 10 to the coil axis Ax can prevent a leak current from flowing through inside of the base body 10 (for example, through the core area 10N).

Next, a coil component 501 according to still another embodiment of the present invention will be described with reference to FIGS. 8 and 9. FIG. 8 is a perspective view schematically showing the coil component 501. FIG. 9 shows a cross section of the coil component 501 in FIG. 8, cut along the line I-I. The coil component 501 differs from the coil component 1 in that it includes a high resistance portion 512a and a high resistance portion 512b instead of the high resistance portion 12.

As shown in FIG. 8 and FIG. 9, the high resistance portion 512a is disposed to contact the external electrode 21, and the high resistance portion 512b is disposed to contact the external electrode 22. In the illustrated embodiment, at least a part of the outer surface of the high resistance portion 512a contacts an inner circumferential surface of each of the flange portions 21b to 21e, and at least a part of the outer surface of the high resistance portion 512b contacts an inner circumferential surface, which is a surface of the base body 10 side, of each of the flange portions 22b. In at least one embodiment of the present invention, the high resistance portion 512a extends from the positive side ends of the flange portions 21b to 21e of the external electrode 21 in the W-axis direction toward a positive side in the W-axis direction. In at least one embodiment of the present invention, the

16

high resistance portion 512b extends from the negative side ends of the flange portions 22b to 22e of the external electrode 22 in the W-axis direction toward a negative side in the W-axis direction

According to the coil component 501, the high resistance portion 512a and the high resistance portion 512b prevent a leak current from flowing between the external electrode 21 and the external electrode 22 along the connecting surface of the base body 10. In a case where electrolytic plating is used for forming the external electrode 21 and the external electrode 22, it is possible to suppress expansion of the plating to the connecting surface of the base body 10. If the plating expands beyond a predetermined area on the external electrode 21 and the external electrode 22 to reach the connecting surface of the base body 10, a short circuit can occur between the external electrode 21 and the external electrode 22. Accordingly, the high resistance portion 512a and the high resistance portion 512b have such a function that can prevent the plating from expanding to the connecting surface of the base body 10 during the manufacturing process of the coil component 501, in addition to a function of increasing resistance between the external electrode 21 and the external electrode 22.

The dimensions, material, and arrangement of the elements described herein are not limited to those explicitly described for the embodiments. The elements are susceptible of modifications for desired dimensions, materials, and arrangements within the scope of the present invention.

Constituent elements not explicitly described herein can also be added to the above-described embodiments, and it is also possible to omit some of the constituent elements described for the embodiments.

The words "first," "second," and "third" used herein are added to distinguish constituent elements but do not necessarily limit the numbers, orders, or contents of the constituent elements. The numbers added to distinguish the constituent elements should be construed in each context. The same numbers do not necessarily denote the same constituent elements among the contexts. The use of numbers to identify constituent elements does not prevent the constituent elements from performing the functions of the constituent elements identified by other numbers.

What is claimed is:

1. A coil component comprising:
a coil conductor including a circling portion extending around a coil axis;
a base body having an outer surface, the outer surface including a first surface, a second surface, and a connecting surface, the first surface intersecting the coil axis and having a long side and a short side, the second surface being opposite to the first surface and spaced apart from the first surface with a distance shorter than the long side, the connecting surface connecting the first surface with the second surface, the base body covering at least the circling portion of the coil conductor;
a first external electrode disposed on the first surface and connected to one end of the coil conductor; and
a second external electrode disposed on the second surface and connected to the other end of the coil conductor,
wherein the base body includes a main body portion and at least one high resistance portion, the main body portion including plural metal magnetic particles and occupying a part of the connecting surface, the at least one high resistance portion occupying an area of the connecting surface other than the part occupied by the

17

main body portion between the first external electrode and the second external electrode, the area extending along an entire length of a circumference of the base body around the coil axis, the at least one high resistance portion having a higher volume resistivity than the main body portion, wherein the at least one high resistance portion is spaced apart from both the first external electrode and the second external electrode, and wherein the first and second external electrodes only contact the first and second end surfaces.

2. The coil component according to claim 1, wherein the circling portion has an outer circumferential surface opposite to the connecting surface of the base body, and

the at least one high resistance portion extends from the connecting surface to the outer circumferential surface of the circling portion.

3. The coil component according to claim 2, wherein the at least one high resistance portion further extends to an inner area of the circling portion.

4. The coil component according to claim 1, wherein the at least one high resistance portion occupies an entire area of the connecting surface between the first external electrode and the second external electrode.

5. The coil component according to claim 1, wherein the at least one high resistance portion includes a first high resistance portion and a second high resistance portion disposed nearer to the second surface than the first high resistance portion.

6. The coil component according to claim 1, wherein the first external electrode includes a first plated layer, and

the at least one high resistance portion is disposed to contact the first external electrode.

7. The coil component according to claim 1, wherein the second external electrode includes a second plated layer, and

the at least one high resistance portion is disposed to contact the second external electrode.

18

8. The coil component according to claim 1, wherein each of the plural metal magnetic particles included in the main body portion includes Fe and at least one element out of Si, Ti, and Zr, the at least one high resistance portion includes plural other metal magnetic particles, each of the plural other metal magnetic particles includes

Fe and at least one element out of Si, Ti, and Zr, and a content ratio of a total of Si, Ti and Zr to Fe in each of the plural other metal magnetic particles included in the at least one high resistance portion is higher than a content ratio of a total of Si, Ti and Zr to Fe in each of the plural metal magnetic particles included in the main body portion.

9. The coil component according to claim 1, wherein the at least one high resistance portion includes plural other metal magnetic particles, and each of the plural other metal magnetic particles includes on a surface thereof an insulating film consisting of insulating material.

10. The coil component according to claim 1, wherein the at least one high resistance portion includes plural other metal magnetic particles, and the plural other metal magnetic particles have a smaller average particle size than the plural metal magnetic particles included in the main body portion.

11. The coil component according to claim 1, wherein a relative magnetic permeability of the at least one high resistance portion is 10% or greater of a relative magnetic permeability of the main body portion.

12. The coil component according to claim 1, wherein a relative magnetic permeability of the at least one high resistance portion is less than 10% of a relative magnetic permeability of the main body portion.

13. A circuit board comprising the coil component according to claim 1.

14. An electronic device comprising the circuit board according to claim 13.
